CYRUS B. STANTON, OF NEW YORK, N. Y.

FEEDING MECHANISM FOR CORK-CUTTING MACHINES.

1,121,685.

Specification of Letters Patent. Patented Dec. 22, 1914.

Application filed January 22, 1914. Serial No. 813,758.

To all whom it may concern:

Be it known that I, CYRUS B. STANTON, a citizen of the United States, and a resident of New York, borough of Brooklyn, county of Kings, and State of New York, have invented a certain new and useful Improvement in Feeding Mechanism for Cork-Cutting Machines, of which the following is a full, clear, and exact specification.

This invention relates to a class of devices adapted to be used with machines for cutting disks of cork.

My invention has for its object primarily to provide a feeding mechanism designed to be employed in conjunction with machines especially used for cutting disks of cork, and which is of a form adapted to be operated in unison with the operation of the machine, whereby cork in sheets may be delivered to the machine so as to be cut into disks of suitable sizes and shapes. This is accomplished mainly by providing a frame in which is reciprocably mounted a carrier provided with one, or a number of fingers, or prongs adapted to intermittently deliver the sheets of cork to the cutters of the machine for being cut into disks when the machine is operated.

Another object of the invention is to provide means adapted to be connected to the operative mechanism of the machine for imparting a reciprocatory movement to the carrier when the machine is operated; and still another object of the invention is to provide means for yieldingly retaining the sheets of cork in the feed mechanism so as to be properly fed by the delivery fingers.

A further object of the invention is to provide a feed mechanism of simple and efficient construction, and which is susceptible of being made in various sizes so as to be adapted for use in conjunction with machines of different types.

With these and other objects in view, the invention will be hereinafter more particularly described with reference to the accompanying drawing forming a part of this specification, in which similar characters of reference indicate corresponding parts in all the views, and will then be pointed out in the claim at the end of the description.

In the drawing, Figure 1 is a side elevation, partly broken away, of one form of feed mechanism embodying my invention. Fig. 2 is a top plan thereof. Fig. 3 is a perspective view of the feed mechanism with

some parts removed therefrom. Fig. 4 is a perspective view of the preferred forms of the delivery elements employed in the mechanism, and Fig. 5 is a fragmentary view, partly in section, showing a form of cork cutting machine with the feed mechanism as used in conjunction therewith.

The feed mechanism has a frame 10 composed of a lower longitudinally disposed bar 11 and an upper longitudinally disposed bar 12 which is spaced on vertical alinement from the lower bar. On the same plane and spaced from the lower bar 11 is a second lower longitudinally disposed bar 13, and also spaced on vertical alinement above the second lower bar is a second longitudinally disposed upper bar 14. Connecting the rear end portions of the lower and upper bars 11 and 12 is a vertical upright 15, and connecting the rear end portions of the lower and upper bars 13 and 14 is another vertical upright 16.

Provided between the central parts of the uprights 15 and 16 is a transverse bar 17 through which is an opening communicating with the opening through an apertured boss 18 extending from the rear surface of the transverse bar 17. Through the openings of the bar 17 and the boss 18 is an adjustably disposed rod 19 of sufficient length to extend inwardly of the frame 10 as well as projecting some distance rearwardly of said frame, and on the end of this rod is rigidly held a block 20. The block 20 is of a size to adapt it to be adjustably moved between two spaced vertically disposed opposed guides, or plates 21 and 22. The plate 21 has its ends secured respectively to the lower and upper longitudinal bars 11 and 12 intermediate the ends thereof, and the plate 22 has its ends secured respectively to corresponding parts of the lower and upper longitudinal bars 13 and 14. Also between the plates 21 and 22 is a movable plate 23 which is approximately the same length as the plates 21 and 22, and said plate 23 abuts against the block 20.

In the frame 10 is reciprocably mounted a carrier 24 having two vertically disposed spaced rods 25 and 26. The rod 25 is freely movable in two registered openings, one of which is provided through the forward end portion of each of the bars 11 and 12, respectively, of the frame, and the rod 26 is freely movable in two registered openings provided through the forward end portion

of each of the bars 13 and 14, respectively. The rods 25 and 26 are of lengths so that their ends extend suitable distances below and above the side bars of the frame to avoid displacement therefrom when being reciprocated, and movable on the upper parts of these rods between the lower and upper side bars of the frame is a transverse bar 31 which may be adjusted to suitable 10 positions on said rods through the medium of set screws 32 and 33. When a sheet of cork, as indicated at 34, is delivered through the machine the cork is passed between the upper side bars of the frame so as to lie 15 against the plate 23, and to yieldingly retain the cork against this plate, upon the transverse bar 31 is provided a spring 35. The spring 35 is disposed in opposed relation to the plate 23, and said spring is formed with 20 curved free ends so that the cork may be moved between these ends of the spring and the plate 23. Also held on the rods 25 and 26 underneath the bar 31 is a second transverse bar 36 to which is rotatably mounted 25 a transverse rod 37 having one of its ends extending beyond one end of the bar. At spaced intervals on the central part of the rotatable rod 37 are held one of the corresponding ends of two fingers, or prongs 38 and 39 each of which is formed to provide 30 teeth, as 40 and 41, on its free end. The fingers 38 and 39 are disposed on similar inclines, and extend so that the toothed ends thereof are in close proximity to the plate 23 underneath the spring 35. During the 35 downward reciprocatory movement of the carrier 24 in the frame of the mechanism, as will be hereinafter more fully explained, the teeth of the fingers 38 and 39 will engage the sheet of cork for directing it also in a downward direction between the plate 23 and the spring 35, and in order to normally serve for permitting the teeth of the fingers to yieldingly engage the cork so as 40 to be released therefrom during the upward reciprocatory movement of the carrier, a spring, as 42, is provided. The spring 42 has one of its ends connected to a sleeve 43 held upon the vertical rod 25, and the other 45 end of said spring is connected to an arm 44 of a sleeve 45 held to the extending end of the rotatable rod 37 of the fingers 38 and 39. Secured to the lower ends of the vertical rods 25 and 26 is a third transverse bar 50 46 having a bolt 47 projecting midway therefrom, and on this bolt is a revoluble wheel 48. Also held on the bolt 47 is a plate 49 having its lower end extending some distance below the frame of the mechanism, 55 and the lower end of the plate is curved, as shown, toward the rear of the frame so as to be contacted by the sheet of cork after passing through the mechanism to prevent it from being directed forwardly of the frame 60 10.

In practice the feed mechanism is employed in conjunction with a cork cutting machine of any suitable type, for instance a form of machine, as indicated at 50 Fig. 5, provided with one or more tubular disk cutters, as 51, adapted to be reciprocated longitudinally, and the reciprocatory movement of these cutters may be controlled by a cam 52 which is revolved through the medium of a shaft 53 driven by any desired mechanism, as 54, which may be used in this class of machines. The feed mechanism is mounted upon the frame of the cork cutting machine in a manner whereby the carrier 24 will be reciprocated in a vertical direction 70 relatively to the longitudinal reciprocation of the cutters 51 so that the cutters will intermittently contact with and cut successive parts of the sheet of cork as it is fed through the feed mechanism. Serving to permit the 75 carrier 24 of the feed mechanism to be reciprocated by the operation of the cutting machine, on a shaft 56 having one of its ends connected to the shaft 53 of the cutting machine is provided a disk 57 which is eccentrically held on this shaft. The disk 57 is disposed so that its peripheral edge is in movable contact with the wheel 48 of the bar 46 of the carrier 24. When the shaft 53 of the cutting machine is rotated by the 80 operation of the machine the shaft 56 and the eccentric disk 57 will be revolved in unison therewith. When the disk is rotated so as to be swung in a direction above the shaft 56 the wheel 48 and the carrier 24 will be moved in an upward direction in the frame of the feed mechanism, and as the transverse bars 31, 36, 46 of the carriers are made of heavy metal the carrier 24 will be directed downwardly by reason of the weight 85 of these bars as well as retaining the engagement of the wheel 48 with the eccentric wheel 57 when the eccentric wheel is swung in a direction below the shaft 56 during the 90 operation of the cutting machine. The carrier will thereby be reciprocated for guiding the fingers 38 and 36 to properly feed the cork so that disks may be cut therefrom by the cutters of the machine. 95 100 105 110 115

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope of the appended claim. 120

Having thus described my invention, I claim as new and desire to secure by Letters Patent:

In a feeding mechanism having a frame adapted to be fixedly mounted on a cork cutting machine, said frame being provided 130

with guides whereby a sheet of cork may be directed through the frame so as to be intermittently moved in the path of the movement of the cutters of the machine, in combination with a carrier composed of two spaced rods mounted in the frame so as to be vertically reciprocated, a transverse bar held to the vertical rods, two spaced prongs mounted on the transverse bar so as to be reciprocably moved when the carrier is reciprocated, and said prongs being adapted to intermittently engage the sheet of cork for transmitting the cork between the guides and in front of the cutters, means provided on the reciprocable rods and normally forcing the prongs in a direction to yieldingly engage the cork, a second transverse bar also held to the reciprocable rods, a wheel pro-

vided on the transverse bar, and a circular disk eccentrically held on a shaft adapted to be connected to the cutting machine whereby the disk may be revolved by the operative parts of the machine, said disk being in revoluble engagement with the wheel, and the said transverse bars being of sufficient weights to retain the wheel and the disk in movable engagement so that the carrier will be reciprocated in the frame when the disk is revolved by the operation of the machine.

This specification signed and witnessed this twenty-first day of January A. D. 1914.
